PULL-ROD CLAMP.

1,073,776.

Specification of Letters Patent.

Patented Sept. 23, 1913.

Application filed September 26, 1912. Serial No. 722,520.

To all whom it may concern:

Be it known that I, DANIEL D. NEVILLE, a citizen of the United States, residing at Kansas City, in the county of Jackson and

5 State of Missouri, have invented certain new and useful Improvements in Pull-Rod Clamps; and I do declare the following to be a full, clear, and exact description of the invention, such as will enable others skilled 10 in the art to which it appertains to make and use the same, reference being had to the accompanying drawings, and to the letters and figures of reference, marked thereon, which form a part of this specification.

15 My invention relates to pull rod clamps, and more particularly to a clamp for connecting the independent members of a sectional pitman, or pump rod, so that a pump, or the like, located at a distance from its 20 power may be operated without lost motion or pounding due to loose connection of the rod sections.

It is the principal object of the invention 25 to provide a clamp of this character of sufficient length to overlie the ends of abutting rod sections sufficiently to provide a substantial bearing surface against the sections, and having means for inclosing heads on the 30 ends of the sections, but being of such construction that the weight of the clamp is limited to a minimum without sacrificing its strength. In accomplishing these objects, I have provided the improved details of 35 structure hereinafter described and illustrated in the accompanying drawings, wherein:—

Figure I is a perspective view of a clamp constructed according to my invention, showing its application to a sectional 40 rod. Fig. II is an end view of same. Fig. III is a central longitudinal section illustrating the seat of the rod heads in the clamp.

Referring more in detail to the parts:— 45 The body of the clamp is formed in two pieces, each comprising a central portion 1, of greatest diameter, having a dome 2 rising therefrom, and provided with a flat top 3. Extending longitudinally from the ends of 50 and merging into the dome 2 is a barrel portion 4, the ends of which are reduced in diameter to form the end channel collars 5, the edges of the barrel 4 and channels 5 merging into a radial rib 6 which extends 55 throughout the length of the clamp.

Extending from the center of each of the end collars 5 to the top of the dome 2 is a stiffening rib 7 which gives the clamp substantially the same strength as though the metal were solid instead of being cut away 60 to form the reduced barrel and the collar portions. The collar portions 5 are concaved at their inner faces to provide channels for receiving the ends of the pull rods, and the barrels are concaved to form a recess 65 back of the collars for receiving the heads of the pull rods and also serving to further reduce the amount of material in the clamp and lighten same.

Each of the clamp members has an aperture 8 opening from the top of its dome through the barrel to the barrel recess, the apertures being inclined inwardly and outwardly from the outer face of the dome in order to still further reduce the material and 70 provide for movement of a bolt so that when a part of the clamp members is in place, as will presently be described, a bolt may be 75 more readily projected through the imperfectly registering apertures.

9 designates pull rod sections, each of which has an end projected through the collar of a clamp, and provided with a head 10 which seats within the barrel recess and engages the shoulder 11 formed by the reduction in diameter between the barrel 4 and collar 5.

The two clamp members are held in place, and to the ends of the pump rod sections, by a bolt 12 having a head 13 bearing against 90 the dome of one of the members, and a nut 14 bearing against the dome of the opposite member, so that when the nut is tightened the members are drawn together and tightened on the ends of the rod. The clamp 95 members are made to fit rods of known diameter, and in forming the collars the concaved recesses are made of less diameter than the rod, so that when the clamp members are placed over the ends of the rod 100 sections the side ribs 6 will not touch each other but will be spaced apart, as illustrated in the drawing, so that when the members are tightened together the collars will bind against the rod and hold same firmly to prevent the sections from slipping in the clamp and consequent pounding of such sections.

In using the clamp, the headed rod sections are laid from the power to the pump, or driven member, and the clamps spaced 110

over the ends of adjacent rods, so that the rod heads will fit within the barrel recesses and abut snugly against the collar shoulders. The clamp bolts are then projected through the paired members and tightened on the rods by the turning on the nuts, it being apparent that as the collar concaves are of less diameter than the rod sections that the side flanges 6 will not meet and that 10 the sections will be clamped firmly between said collars.

As the rods are usually combined with the motor and pump, so that the working stroke of the pump occurs while the rod is 15 being pulled and not when it is being pushed the heads of the rod sections will pull against collar shoulders so that the frictional grip of the clamp against such sections is not required to carry the burden of 20 the work.

It is also apparent that by constructing the clamp as described, the center and side ribs will strengthen the members so that considerable material may be eliminated 25 without weakening the clamp, thereby effecting a saving not only in the material alone, but also in carrying charges.

Having thus described my invention, what I claim as new therein and desire to 30 secure by Letters Patent, is:—

1. The combination with a longitudinally split clamp having transverse apertures and comprising body and end collar members of different diameter, forming shoulders at the

ends of the body portions, of a bolt extending through said apertures and through the interior of the body, whereby the split members are held together, and separate pull rods lying within opposite collar members, and having heads located within the clamp body and bearing against the collar shoulders; with the inner ends of said heads spaced from the connecting bolt. 35 40

2. The combination with a split clamp, having a central portion and end collars of different diameters, forming shoulders, and having transverse apertures, tapered outwardly from the interior of the body, of a bolt extending through said apertures, and separate pull rods lying within the end collars and having heads bearing against said shoulders, and spaced from the bolt, for the purpose set forth. 45 50

3. The combination with clamp members, each comprising an interior recess and end channels and having a central transverse and outwardly tapered aperture, of a bolt adapted for projection through the tapered channels whereby lateral movement of the clamp on the bolt is afforded, substantially 55 60 as set forth.

In testimony whereof I affix my signature in presence of two witnesses.

DANIEL D. NEVILLE.
